ANUS SPRAYING APPARATUS

Enrique Monserrat, Manila, Philippine Islands

Application August 22, 1949, Serial No. 111,659

2 Claims. (Cl. 4—7)

1

This invention relates to new and useful improvements and structural refinements in accessories for use with toilet bowls, and the principal object of the invention is to provide an apparatus of the character herein described such as may be conveniently and effectively employed for spraying the region of the anus after the toilet is used, thus retaining that region in a highly sanitary condition and preventing staining of underclothes.

An important feature of the invention, therefore, resides in the provision of an anus spraying device including an upwardly directed spraying nozzle which is disposed within the toilet bowl when the use thereof is desired, but which may be quickly and easily swung to an inoperative position when it is not needed.

Some of the advantages of the invention lie in its simplicity of construction, in its convenient and efficient operation, and in its adaptability for use with toilet bowls of different sizes and types.

With the above more important objects and features in view and such other objects and features as may become apparent as this specification proceeds, the invention consists essentially of the arrangement and construction of parts as illustrated in the accompanying drawings, in which:

Figure 1 is a perspective view of the toilet bowl, the same being partially broken away so as to reveal the invention in situ therein.

Figure 2 is a perspective view, similar to that shown in Figure 1, but illustrating the invention in an operative position.

Figure 3 is a fragmentary elevational detail of the invention.

Figure 4 is a top plan view of the subject shown in Figure 3.

Figure 5 is a fragmentary cross sectional view of a nozzle controlling element used in the invention, and

Figure 6 is a fragmentary perspective view illustrating a modified embodiment of the element shown in Figure 5.

Like characters of reference are employed to designate like parts in the specification and throughout the several views.

Referring now to the accompanying drawings in detail, the invention consists of an anus spraying apparatus designated generally by the reference character 10, this being intended for use in association with a toilet bowl 12 of any conventional type, the apparatus 10 embodying in its construction a substantially upright water sup-

ply pipe 12 provided at its lower end with a twin valve assembly 14 which, in turn, is connected to cold and hot water pipes 16, 18 respectively, so that by simply manipulating the two units of the twin valve 14, water of suitable temperature may be admitted into the pipe 12. In other words, the valve 14 is a mixing valve for hot and cold water, as will be clearly apparent.

A coupling member 20 is rotatably mounted on the upper end portion of the pipe 12 and a water supply conduit 22 extends laterally from this coupling member, being equipped at its outer end with an elbow 24 which, in turn, has swingably connected thereto a substantially J-shaped conduit extension 26. The free end of this extension is provided with a suitable spraying nozzle 28, it being noted that this nozzle, when in an operative position, is disposed within the toilet bowl 12 and is directed upwardly, as shown in Figure 1. However, by virtue of the rotatability of the extension 26 relative to the elbow 24, the extension together with the nozzle 28 may be swung from an operative, vertical position to an inoperative, substantially horizontal position as indicated by the phantom line 30 in Figure 4 and by the corresponding solid lines in Figure 2. Moreover, by virtue of the rotatability of the coupling member 20 on the pipe 12, the conduit 22, including the extension 26, is swingable from an operative position over the bowl 12 to an inoperative position at one side of the bowl (see Figure 2), it being understood that the extension 26 is swingable upwardly to sufficient height as to provide clearance above the upper edge of the bowl (or the toilet seat 32) to facilitate swinging of the entire unit to its inoperative position as shown in Figure 2.

Means are provided for simultaneously controlling the swinging movement of the extension 26 and of the conduit 22, these means involving the provision of an upwardly extending stem 34 which is secured as at 36 in a protuberance 38 provided on the coupling member 20, while an actuating element 40 is slidably and rotatably positioned on the stem 34, as is best shown in Figure 5.

The element 40 has secured thereto a pulley 42 and a cable 44 is windable on this pulley, one end of the cable being connected to the extension 26 by a clamp 46 while an intermediate portion of the cable passes through suitable guiding eyes 48 provided on the conduit 22.

It will be readily understood from the foregoing that by simply rotating the element 40 in the direction of the arrow 50 (see Figure 4)

the extension 26 will be drawn upwardly as at 52 (see Figure 3) to its inoperative position, while the conduit 22, of course, remains stationary.

However, by virtue of the same element 40, the conduit 22 may also be swung to its inoperative position, this being effected by providing the lower end of the element 40 and the protuberance 38 of the coupling member 20 with coacting driving members or toothed dogs 54, 56 respectively, which dogs are normally disengaged from each other by means of a compression spring 58 which is disposed in a cavity or chamber 60 provided in the element 40 (see Figure 5). One end of the spring 58 is rigidly secured to the upper end of the stem 34, while the remaining end of the spring, that is, the upper end of the spring bears against a plug 62 provided on the element 40. As a result, the spring 58 urges the element 40 to an upwardly slid position on the stem 34, thus disengaging the driving members or dogs 54, 56 and permitting actuation of the extension 26 by a simple rotation of the element 40 on the stem 34.

However, when the element 40 is pressed downwardly on the stem as indicated at 64, the dogs 54, 56 are brought in engagement, and subsequent rotation of the element 40 will swing the entire unit, that is, the conduit 22 and the extension 26 to an inoperative position, as indicated at 66 in Figure 4.

It is to be understood that matters may be arranged so that the apparatus may be installed at either side of the toilet bowl, and it is to be also noted that in order to facilitate actuation of the extension 26 by the element 40 without any tendency to swing the conduit 22 to its inoperative position, a leaf spring 66 may be secured to the upper end portion of the pipe 12, so as to frictionally engage suitable serrations 68 provided on the coupling member 20, whereby rotation of the coupling member and conduit 22 on the pipe 12 will be resisted.

In a simplified embodiment of the invention a modified actuating element may be used, this element being designated by the reference character 70 in Figure 6, which is similar to the element 40 but in place of the pulley 42, the element 70 is equipped with a radially projecting arm 72 to which the cable 44 is connected as at 76, the length of this arm being sufficient to facilitate movement of the extension 26 between its operating and inoperative positions.

It is believed that the advantages and use of the invention will be clearly apparent from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

- 15 1. An anus spraying apparatus for toilet bowls, said apparatus comprising a water supply pipe and a shut-off valve thereon, a coupling member provided on said pipe and rotatable about a vertical axis, a horizontal water supply conduit 20 carried by said coupling member and swingable from an operative position above a toilet bowl to an inoperative position at one side of the latter, a substantially J-shaped extension connected to the free end of said conduit and swingable about a horizontal axis from an operative vertical position in the stated bowl to a substantially horizontal inoperative position above the upper edge of the latter, an upright stem provided on said coupling member, an actuating 25 element rotatably and slidably mounted on said stem, means operatively connecting said element to said extension for swinging the latter by the rotation of said element, coacting driving members provided on said element and on said coupling member and engageable upon sliding of said element, and resilient means for disengaging 30 said driving members.
- 35 2. The device as defined in claim 1 together with means for resisting rotation of said coupling 40 member on said supply pipe.

ENRIQUE MONSERRAT.
